UNITED STATES PATENT OFFICE

CHARLES ZABEL, OF CORAOPOLIS, PENNSYLVANIA, ASSIGNOR, BY MESNE ASSIGNMENTS, TO WOLVERINE SUPPLY & MANUFACTURING COMPANY, OF PITTSBURGH, PENNSYLVANIA

BALL-OPERATED MECHANICAL TOY

Application filed January 12, 1928. Serial No. 246,152.

This invention relates to mechanical toys, and particularly to that class of toys wherein mechanical action is secured by the transfer of a ball from a higher plane to a lower one.

In toys of this class as now generally constructed there is provided an elevated ball receiving trough and a mechanism designed to be operated when a ball is transferred from the elevated trough to a vertically swinging lever. The weight of the ball on the vertically swinging lever rocks the lever, swinging it down until the lever is at its lowermost point when the ball is discharged into a receiving trough, or on to the base of the toy where it is free to roll away. The construction requires the manual transfer of the balls from the base of the toy to the elevated receiving trough.

According to the present invention there is provided a toy having a reversible ball magazine wherein the entire series of balls may be transferred from a lower position to an elevated position by manual actuation of the magazine without requiring that the operator touch the balls or handle them in any way.

According to the present invention there is also provided a novel escapement mechanism for feeding the balls one at a time to the transfer lever which actuates the toy.

The invention further contemplates the provision of a toy of novel construction and operation which may be cheaply manufactured.

The invention may be readily understood by reference to the accompanying drawings wherein

Figure 1 is a front elevation of a toy embodying my invention;

Figure 2 is a front elevation of the actuating mechanism of the toy with the toy figures removed;

Figure 3 is a transverse section in the plane of line III-III of Figure 1;

Figure 4 is a transverse vertical section in the plane of line IV-IV of Figure 1;

Figure 5 is a similar section in the plane of line V-V of Figure 1;

Figure 6 is an elevation of the ball magazine detached from the toy;

Figure 7 is a view partly in section and partly in elevation of the ball magazine shown in Figure 6, the view being along the plane of line VII-VII of Figure 6;

Figure 8 is a view showing a slightly modified form of toy; and

Figure 9 is an enlarged elevational view of the escapement mechanism.

The toy as shown in the drawings is comprised of a base member 2 which preferably has downwardly turned side flanges 3 and 4. Mounted against the rear flange 4 is a wall 5 which may be painted to form a background for the action of the toy. Secured by a pivot 6 to the outside of the back plate or wall 5 is a reversible ball magazine. The reversible ball magazine has a cross strip 7 through which the pivot 6 passes. At each end of the cross piece 7 is a closed chute or ball receiving trough 8. The chutes or troughs 8 diverge away from the member 7. The outer ends of the members 8 are connected by a cross brace 9. Each of the chutes or magazine members 8 is closed at its outer end, as indicated at 10 in Figure 6. Each of these magazine members has an opening 11 in the side face thereof, as also clearly shown in Figures 6 and 7. The openings 11 are in line with each other and with the pivot 6 for the magazine assembly. The inner ends of the members 8 are closed by a partition 12, best shown in Figure 7, adjacent the opening 11.

In the back wall 5 in line with the pivot 6 is an upper opening 13 which registers with the opening 11 of the uppermost member 8 of the reversible magazine. Correspondingly positioned below the pivot 6 is a lower opening 14 which registers with the opening 11 of the lower member 8 of the magazine.

Extending forwardly from the upper opening 13 is a narrow projection or lug 15 with an upwardly turned stop 16 at its outer end. For cooperation with the lug 15 is an escapement member 17 pivoted to the back wall 5 at 18. The escapement member 17 has a forwardly projecting extension 19 thereon. It also has a downwardly extending lug 19a thereon adapted to oscillate across the open-

ing 13. The escapement member 17 is provided with an operating arm 20 with a lug 21 at the outermost end thereof.

Secured to the front of the back wall 5 in front of the lower opening 14 is a receiving trough or pan 22 with an upstanding lug 23 thereon. The pan 22 is inclined toward the opening 14 so that balls which are dropped into it will roll through the opening 14 and into the lower member 8 of the reversible magazine. Secured to the back wall 5 and projecting forwardly therefrom is a supporting arch 24. A shaft 25 has one end supported in the arch 24 at 26 and has its other end supported in a forwardly pressed portion 27 of the back wall 5. Pivotaly supported on the shaft 25 is an oscillating frame 28 having a depending arm 29. The shaft 25 passes through a lug at one end of this frame at 30 and through the arm 29 at 31, thereby providing the pivotal support for the frame. Secured to the frame 28 is an arm 32 which has a ball receiving loop 33 at one end thereof.

The lug 21 on the arm 20 of the escapement member 17 is located in the path of travel of the oscillating arm 32. The operation may be easily followed by reference to Figure 2. With the arm 32 in the full line position shown in Figure 2, the escapement member 17 is in its lowermost position. The lug 15 is of just sufficient width to allow a single ball to roll from the upper member 8 of the magazine through the upper port 13 onto the lug 15. The ball is retained on the lug 15 by the extension 19 of the escapement member 17. As the ball receiving end 33 of the lever 32 is rocked upwardly, the lug 21 engaging on the lever 32 causes the escapement member 17 to be lifted or swung about its pivot 18. The extension 19 rocks part way across the opening 13 to prevent another ball from pushing out, and when the escapement member 17 has been lifted far enough, the ball drops into the ball receiving loop 33 at the end of the lever 32, the lever then being rocked to the dotted line position shown in Figure 2 where the ball receiving loop 33 is at the uppermost limit of its travel. The weight of the ball into the loop 33 causes the lever 32 to rock down. When the lever 33 reaches the lower limit of its travel, as indicated by the second dotted line position shown in Figure 2, the extension 23 of the pan 22 projects through the loop 33 and dislodges the ball therefrom. The ball drops into the pan 22 and rolls from the pan through the port 14 into the lower member 8 of the reversible magazine. When the ball has been discharged from the end 33 of the lever, it is overbalanced by the mechanism hereinafter described and swung upwardly to receive the next ball and the cycle of operation is repeated. This action continues so long as any balls remain in the upper magazine 8. When

the balls 8 have been exhausted from the upper member 8 of the magazine they will have all been transferred to the lower member 8 of the magazine. The operator then swings the magazine about the pivot 6 from the dotted line position shown in Figure 2 to the dot and dash line position shown in this figure. The positions of the arms 8 are then reversed, and the operation of the toy can be repeated.

When the lever 32 rocks, it rocks the entire frame 28 with the downwardly extending arm 29, and this motion can be utilized to produce any desired action for the toy.

In the construction shown in Figure 1, the frame 28 has a bar 35 secured thereto with a toy figure at each end thereof to represent a seesaw. In addition to this, the supporting arch 24 carries a Y shaped member 36. From each arm of the Y is pivotally suspended a frame 37 and the frames 37 are connected at the lower ends by a swing member 38. The swing member 38 has a depending lug 39 thereon which carries a pin 40 projecting through a slot 41 in the arm 29. The swing carries two figures 40, representing children seated in the swing. When the lever 32 rocks, rocking the oscillating frame 28, the arm 29 oscillates and imparts a swinging movement to the frame 38.

In addition to this the base 2 carries a vertically extending support 42 from which is hung a swing 43. Each swing 43 has a figure 44 seated therein. Depending from the swing 43 at one side thereof is an extension 45 that passes through a slot 46 in the base 2. The lower ends of the extensions 45 are connected through links 47 concealed under the base with a downwardly projecting extension 48 on the swing frame 38.

The entire action of the toy as thus described depicts a playground. As the lever 32 is actuated the swing 38 moves back and forth, the seesaw 35 rocks and each of the swings 43 are oscillated. This is just one type of action which may be utilized in the toy. In the arrangement shown in Figure 8 the mechanism is the same as that previously described, and similar reference numerals have been used to represent the corresponding parts. In this arrangement 32 is the oscillating lever with the ball receiving loop 33 at its outer end. This lever is carried on a rocking frame construction 28 with a depending arm 29. The arm 29 projects through a slot in the base 2. Mounted on the base at various points are toy figures representing various artisans at work. Some of these figures have a lever 50 connected thereto and extending through slots in the base 2. The various levers 50 secured to the different figures are all connected to the lower end of the arm 29 through links 51 located under the base. In the particular arrangement shown, the rocking of the lever 32 causes the minia-

ture figures 52 and 53 to alternately hit an anvil with hammers, while the figure 54 has an action simulating a wood chopper. Figure 55 works a saw 56, and another figure 57 is moved through the reciprocation of the saw.

The particular action or arrangement or disposition of the figures can be widely varied, the particular arrangements shown being merely illustrative of the principle of my invention. Any arrangement of the figures, or any suitable single figure can be arranged on the base for operation from the oscillating frame.

The toy can be cheaply constructed. Because of the provision of the reversible ball magazine, the handling of the balls is eliminated. The shifting of the magazine from one position to the other can be easily done by even a very small child. To limit the reversing movement of the magazine there are two lugs 58 projecting from the back wall. One of these lugs 58 limits the swinging movement of the frame in one direction so as to assure of the ports 11 registering with the upper and lower ports 13 and 14, and the other lug is correspondingly positioned to limit the swinging movement of the magazine in its other position.

The escapement mechanism is extremely simple, and allows for the release of only one ball at a time. The location and arrangement of this escapement where it can be seen gives added action to the toy.

While I have specifically described particular embodiments of the invention, it will be understood that various changes and modifications may be made in the construction and arrangement of parts within the contemplation of my invention and under the scope of my appended claims.

I claim:

1. A mechanical toy comprising a base, a ball operated mechanism on the base, a vertical plate carried on the base having upper and lower openings therein, a ball escapement mechanism disposed in front of the upper opening, a ball receiving means in front of the lower opening, and a magazine pivotally supported on said vertical plate between the openings, said magazine having two ball receiving channels with openings therein that register with the openings in the plate when the magazine is in either of its operating positions.

2. In a mechanical toy, a support, a vertical plate thereon, a reversible ball magazine pivotally supported on one side of the plate, said magazine being movable between two operating positions, a ball operated mechanism on the other side of the plate, said plate having an upper opening therein and a lower opening therein, a ball escapement mechanism associated with the upper opening, a ball receiving means associated with the lower opening, said ball operated mech-

anism including a vertically swinging lever having a ball receiving means at one end thereof, said end of the lever being movable between the ball escapement means and the ball receiving means of the upper and lower openings respectively, whereby it may receive a ball at the upper opening and discharge the ball at the lower opening.

3. In a mechanical toy, a support, a vertical plate thereon, a reversible ball magazine pivotally supported on one side of the plate, said magazine being movable between two operating positions, a ball operated mechanism on the other side of the plate, said plate having an upper opening therein and a lower opening therein, a ball escapement mechanism associated with the upper opening, a ball receiving means associated with the lower opening, said ball operated mechanism including a vertically swinging lever having a ball receiving means at one end thereof, said end of the lever being movable between the ball escapement means and the ball receiving means of the upper and lower openings respectively, whereby it may receive a ball at the upper opening and discharge the ball at the lower opening, and a mechanism connected with and operated by the said lever.

4. In a mechanical toy, a base, a vertical plate thereon, said plate having a ball delivery opening and a ball receiving opening therein, a reversible magazine at the back of the plate, a vertically swinging lever mounted on the support in front of said plate, one end of said lever being movable between the ball delivery opening and the ball receiving opening, a ball supporting element on the plate projecting forwardly from the ball delivery opening, and an escapement member pivotally supported on the plate movable from a ball holding to a ball releasing position, said member having an extension thereon adapted to move across the delivery opening when said escapement member is rocked to a ball releasing position and to uncover the opening when the member is rocked to ball retaining position, said escapement member also having a forwardly projecting extension thereon for cooperation with the ball support when the escapement member is in ball retaining position but being adapted to be moved away from the ball support when the escapement member is moved to ball releasing position, and an extension on said escapement member for engagement with said lever whereby the escapement member is operated by oscillation of said lever.

5. The combination with a ball operated mechanical toy having a vertical plate thereon, of a reversible ball magazine pivoted to one side of the plate, said ball magazine being movable from one operating position to another and having two ball retaining channels therein, one of which is arranged to re-

ceive balls when the other is in position to deliver balls, said plate having an upper opening therein through which balls pass from the magazine, said plate also having a lower opening therein through which balls are delivered to the said magazine, and an escapement member cooperating with the upper opening.

6. In a mechanical toy, a support, a ball operated mechanism on the support including a rocking frame, a vertical flat plate on the support, a reversible ball magazine having ball retaining channels on the back of the plate, said plate having an opening therein through which balls may pass from the magazine to the rocking frame of the toy, and a single escapement element pivotally secured to the plate actuated by the rocking frame for delivering balls one at a time to the rocking frame from any of the ball retaining channels.

7. In a mechanical toy, a support, a ball operated mechanism on the support, a reversible ball magazine movably carried on the support for delivering the balls to the mechanism and receiving balls from the mechanism, and a single escapement passage for controlling delivery of the balls.

8. In a mechanical toy, a base, a rocking frame supported above the base having an extension thereon projecting through the base, toy figures movably supported above the base, means extending under the base connecting the figures with said extension whereby the figures are caused to move when the rocking frame is operated, and a ball mechanism for rocking the frame including a ball transfer arm on the rocking frame, a reversible ball magazine having two ball delivery channels, and a single escapement element adapted to control delivery of the balls to the transfer arm.

In testimony whereof I have hereunto set my hand.

CHARLES ZABEL.
